JOHN PRIMROSE, OF NEW YORK, N. Y., ASSIGNOR TO POWER SPECIALTY COMPANY,
OF NEW YORK, N. Y., A CORPORATION OF NEW YORK.

DAMPER CONTROL FOR OIL STILL.

1,425,896.

Specification of Letters Patent. Patented Aug. 15, 1922.

Application filed September 16, 1920. Serial No. 410,652.

To all whom it may concern:

Be it known that I, JOHN PRIMROSE, a citizen of the United States of America, residing at New York, in the county and 5 State of New York, have invented certain new and useful Improvements in Damper Controls for Oil Stills, of which the following is a full, clear, and exact description.

- 10 In an application filed by me on June 5, 1920, Ser. No. 386,733, to which I now refer for purpose of more fully illustrating the nature and purpose of the invention which forms the subject of the present application 15 for Letters Patent, I have shown a known form of fractional oil still in which a plurality of successive banks of tubes or heating surfaces are exposed to a gradually increasing temperature and in which provision is made for taking off the vapor 20 formed in each bank. The nature of the vapors so taken off differs according to the temperature to which the oil is subjected, and hence, as is well understood, such temperatures should be maintained uniform or 25 constant in each bank.

In the present case I have shown merely an outline illustration of a typical form of fractional still, omitting for simplicity's 30 sake the details of the means for taking off the vapors and other means which in practical operation are necessary or desirable. This is done for the reason that my present invention is merely an improvement in the 35 means for controlling the amount of heat imparted to or absorbed by each bank of tubes in such a form of still.

My improvement consists in the combination with the series of banks of tubes or 40 heating surfaces of movable dampers in the nature of baffles which may be adjusted as required so as to cause more or less of the hot furnace gases to sweep any given bank and thereby control the quantity and effect of the heat received and absorbed.

This improvement I have illustrated in the accompanying drawing in which the figure is a central vertical section of a fractional still with my improvement applied 45 thereto.

The special construction, arrangement and mode of operation of the still proper are not matters of controlling importance to my invention. It is only necessary that 50 there be a plurality of banks of tubes or

heating surfaces 1, 2, 3, etc., so disposed, as, for example, in the heating chamber 4 above the fire chamber 5 and through which the hot gases pass, as to undergo different heating effects, usually a gradually increasing temperature effect derived from the action of the gases on the oil passing in series through the said banks and sweeping the tubes therein.

In such still it may be and usually is 65 desired to take off from each bank such vapors as may be liberated therein, and as the nature of each vapor so taken off should be fixed and uniform, it is essential that the oil therein be subjected to uniform conditions of heat. This may vary for various 70 reasons. The nature of the fire, the character of the oil, the velocity of flow and the like, and to regulate such heat conditions to secure uniform results, I place over 75 each bank of tubes in the space not occupied by said bank a damper or baffle of refractory material 6, which is suspended by a wire or chain 7 passing over pulleys 8 and carrying counterbalance weights 9. 80

The dampers pass through suitable openings in the top wall of the chamber 4, and in their lowermost position practically close the open passage or space between the top of a bank and the wall. If a given bank 85 is exposed to too great a heating effect the damper above it is raised whereby more or less of this passage is opened and the hot gases, following the path of least resistance, flow through the same, or are shunted 90 around the bank. On the other hand lowering a damper and closing this passage compels the gases to flow chiefly through the spaces between tubes of the bank and thus such tubes are swept by a greater portion of such gases and the temperature 95 of the oil therein correspondingly raised.

This is the principle of my improvement. Obviously the same ultimate object may be secured in substantially the same way by 100 means differing widely in specific construction from those herein shown. I do not intend therefore to limit the invention to the specific means shown and herein described.

105 What I claim as my invention is:

1. In a fractional still, the combination with a chamber for the passage of the hot furnace gases, of a plurality of banks of tubes or heating surfaces supported but not 110

occupying all of the sectional space therein, of a series of refractory baffles suspended in vertical line with the said banks in the spaces not occupied by the same and adjustable to vary the passage through such spaces, whereby more or less of said spaces may be closed or opened and the proportion of hot gases sweeping the banks thereby varied and controlled.

10. 2. In a fractional still, the combination with a chamber for the passage of hot gases, of a plurality of banks of tubes or heating

surfaces therein, but not occupying all of the space therein, of a series of refractory baffles suspended over the banks of tubes in the spaces not occupied by the banks of tubes and adjustable through openings in the top wall of the chamber for closing or opening more or less of said spaces for the purpose set forth.

In testimony whereof I hereto affix my signature.

JOHN PRIMROSE.
